P H. COURVOISIER, OF PARIS, FRANCE.

Letters Patent No. 83,935, dated November 10, 1868.

IMPROVEMENT IN FASTENERS FOR GLOVES.

The Schedule referred to in these Letters Patent and making part of the same.

To all whom it may concern:

Be it known that I, PH. COURVOISIER, of Paris, in the Empire of France, have invented a new and improved Fastening for Gloves and other articles; and I do hereby declare the following to be a full, clear, and exact description thereof, which will enable those skilled in the art to make and use the same, reference being had to the accompanying drawing, forming part of this specification, in which drawing—

Figure 1 represents a sectional side elevation of my fastening.

Figure 2 is an inverted plan thereof.

Figure 3 is a top view thereof.

Similar letters indicate corresponding parts.

This invention relates to a fastening for gloves or other articles of wearing-apparel, which is composed of a hollow dumb-bell-shaped cap, struck up of sheet-metal, and provided with points, which serve to fasten the same to one part of the glove or other article, in combination with a spring-bolt, working in the hollow cap, and with a button, which is also struck up of sheet-metal, and provided with points, which serve to fasten the same to the other part of the glove or other article, and which button is also provided with a rounded head, and with a neck, in such a manner that, when the hollow cap, with its spring-catch, is fastened to one and the button to the other part of a glove or other article, and the loose end of the cap is pressed down over the button, the spring-catch drops into the neck, and the glove or other article is fastened, and, by pushing the spring-catch back against the action of its spring, the cap is released, and the glove or other article becomes unfastened.

A represents a cap, which is struck up, of sheet-metal, in the form shown in the drawing, or in any other convenient form or shape.

One end of this cap is provided with a series of points, *a*, which are passed through the article to which the fastening is to be attached, and then turned under, as shown in fig. 1.

In the interior of this cap is placed a bolt, *b*, which is retained in position by a button, *c*, and which is subjected to the action of a spring, *d*, as shown in figs. 1 and 2.

The button *c* moves in a slot in the cap, so that, by pressing on said button, the bolt *b* can be forced back against the action of the spring *d*.

The loose end of the cap is of such a form that it can be made to cover up the button *B*, which forms the second main part of my fastening.

This button is struck up of sheet-metal, and provided with points, *e*, which serve to fasten the same to the glove or other article, as shown in fig. 1 of the drawing.

The head of said button is rounded off, and it is provided with a neck, *f*, to receive the outer end of the bolt *b*.

The cap *A* is secured to one and the button *B* to the other part of the glove or other article to be fastened, and, by passing the loose end of the said cap over the button, the bolt *b* is caused to catch in the neck *f* of the button *B*, and the glove or other article is fastened. By pressing the small button *c* back, the bolt *b* is caused to release the neck of the button *B*, and the cap *A* becomes unfastened.

Having thus described my invention,

What I claim as new, and desire to secure by Letters Patent, is—

The cap *A*, provided with points *a*, and containing the spring-bolt *b*, in combination with the button *B*, provided with points *e*, and with a neck, *f*, substantially as and for the purpose described.

PH. COURVOISIER.
